S. B. ELLITHORP.

Design for the frame of a Sawing Machine

Patented Sept. 27. 1859.

W. H. Jones
Francis S. Dow
Sidney Dow

S. B. Ellithorp

Ms. 1149

Solomon B. Ellithorp, of New York, N.Y.
Letters Patent No. 1149. Dated Sept. 27, 1859.

The schedule referred to in these Letters Patent and making part of the same.

To all whom it may concern:

Be it known that I, Solomon B. Ellithorp, of the City, County, and State of New York, have invented or produced a new and original design for a Sewing Machine and I do hereby declare that the following is a full and exact description of the same reference being had to the accompanying Photographic impression, serving as a drawing of the same and making part of this Specification.

The purpose of the article, shown in the drawing, and the subject of the design, is to contain the working parts of a sewing machine, and it is made in the form of the letter G, with its faces ornamented as shown. But one half or portion of the width of the letter is shown in the drawing, a duplicate part (reversed) forming the opposite portion of the letter so that both of its sides shall present the same appearance.

What I claim is the design for a sewing machine illustrated and shown in the accompanying drawing.

Witnesses.
